METHOD FOR THERMAL POLYMERIZATION
OF HYDROCARBONSJohn W. Throckmorton, Wilton, Conn., assignor
to The Pure Oil Company, Chicago, Ill., a cor-
poration of Ohio

Application June 21, 1938, Serial No. 280,253

2 Claims. (Cl. 196—10)

This invention relates to improvements in the thermolytic conversion of hydrocarbon fluids and is more particularly concerned with improvements in thermal polymerization of hydrocarbon gases to hydrocarbons boiling within motor fuel boiling range.

In the conversion of hydrocarbon fluids by processes which depend upon thermal means alone for effecting conversion reactions, it has become the practice to recirculate certain low molecular weight hydrocarbons, the boiling points of which are below the usual motor fuel boiling range, to the conversion zone in order to improve the yield of liquid product. These hydrocarbons may be composed of varying proportions of hydrocarbons unaffected by the process and/or of intermediate products formed as a result of the thermal treatment. It has become general practice in the operation of thermal polymerization plants to separate from the recycle gases, hydrogen, methane and C₂ hydrocarbons, since it was believed that these gases interfered with the reaction or were largely unaffected by the conditions of temperature, pressure and reaction time favorable to successful polymerization of higher molecular weight hydrocarbons, particularly the C₃ and C₄ hydrocarbons, which hydrocarbons generally comprise the principal constituents of the charging stock of thermal polymerization processes. It has further been established that operating conditions most suitable for effecting efficient cracking and polymerization vary with the particular hydrocarbons undergoing treatment. For example, ethane requires a much higher cracking temperature to form unsaturated compounds which will polymerize than do the higher boiling hydrocarbons as propane and butane. In general, the greater the number of carbon atoms in the compound, the less drastic is the treatment required to decompose it, particularly with the view of forming unsaturated hydrocarbons. This has been particularly clearly shown by investigators who have worked with pure hydrocarbons such as ethane, propane and butane.

It has likewise been shown that, if a mixture of low molecular weight paraffinic hydrocarbons is processed at a temperature that produces substantial conversion of the member of lowest molecular weight, the yield of motor fuel boiling range hydrocarbons produced from the higher molecular weight hydrocarbons is greatly diminished due to coke formation and/or formation of polymers of higher than motor fuel boiling range. Thus the prior art teaches that it is an advantage in the conversion of hydrocarbon gas to elim-

inate C₂ hydrocarbons and lighter gases from the charge and from the gases recycled to a conversion process. Whether or not the conversion temperature is the only criterion for determining what gases shall be recycled to the conversion zone may be a matter of opinion but in any event the general commercial practice in the art of converting low molecular weight hydrocarbons to hydrocarbons boiling within the motor fuel boiling range shows that it is the accepted practice to remove C₂ hydrocarbons as well as methane and hydrogen from the hydrocarbons recycled to the conversion zone.

I have now found that if C₂ hydrocarbons are included in the gases recycled to the conversion zone of a thermal polymerization process designed to convert low boiling hydrocarbons to hydrocarbons of motor fuel boiling range and if essentially complete recovery of the C₃ hydrocarbons from the conversion products is practiced and these C₃ hydrocarbons are included as a constituent of the gases recycled, a surprisingly high yield of hydrocarbons boiling within motor fuel boiling range results. The improvement in yield is especially noticeable when charging hydrocarbon gases that are low or substantially free of unsaturates. By low in unsaturates I mean a gas which does not develop sufficient heat during reaction under the conditions herein specified to raise the temperature of the products undergoing reaction. This will generally be around 40% or less of unsaturates.

It is an object of this invention to produce hydrocarbons boiling within motor fuel boiling range from hydrocarbon gases.

Another object of this invention is to provide a method for increasing the yield of motor fuel hydrocarbons obtainable from the thermal conversion of low boiling hydrocarbons.

It is a further object of this invention to provide a method for increasing the yield of motor fuel hydrocarbons obtainable from the thermal conversion of low boiling olefin-containing hydrocarbons in which the proportion of olefins is relatively small.

Another object of this invention is to provide a process whereby to obtain higher yields of hydrocarbons useful as motor fuel without substantially increasing operating costs.

Other objects and advantages will become apparent from the following description of my process and the accompanying drawing of which the single figure is a diagrammatic side elevational view of apparatus suitable for carrying out the invention.

Although the invention will be described in connection with polymerization of hydrocarbon gas consisting chiefly of saturated C₃ and C₄ fractions, it is to be understood that the invention is applicable to the treatment of hydrocarbon gases in which either paraffinic or olefinic hydrocarbons preponderate.

Referring to the drawing, the numeral 1 indicates a line controlled by valve 2 through which gas is charged to the system. This gas may be gas from refinery operations such as oil cracking, or from natural gas, or a mixture thereof, and consists predominantly of C₃ and C₄ hydrocarbon fractions. The gas may be charged under pressure of approximately 200 to 500 pounds per square inch. The gas passes from line 1 and valve 2 and is cooled by passage through the cooler 4 from which it passes to feed tank 5. In feed tank 5 the gases may be in substantially liquid condition or in a condition of mixed gas and liquid, depending upon the composition of the gas and the conditions of temperature and pressure maintained. Usually the temperature will be from 70° to 120° F. and the pressure from 200 to 500 pounds per square inch. The liquefied gas is withdrawn from the feed tank 5 through line 7 by means of pump 9 in which the gas is raised to the desired pressure for charging to the conversion zone. This pressure may be from approximately 200 to 2500 or more pounds per square inch. The compressed gas which is substantially in the liquid state is charged through heat exchanger 11 wherein it passes in indirect heat exchange with hot products from the reaction coil which will be subsequently described and may be preheated to a temperature of 600° to 900° F. The preheated gas leaves the exchanger through line 13 and passes into the inlet of heating coil 15 located in furnace 17. In the heating coil the gases are heated while maintained under the aforesaid pressure, to temperatures ranging from approximately 950° to 1250° F., depending upon the pressure, the composition of the charge and upon the nature of the product desired. A temperature range of 1025° to 1125° F. has been found to be particularly effective on a charge of hydrocarbon gas composed principally of propane and butane. If high pressures are employed, the temperature will not be substantially in excess of 1100° F. If low pressures of the order of 350 pounds per square inch are employed, the temperature will preferably be from 1100° to 1250° F.

From the heating coil 15 the heated gases pass to reaction coil 19 wherein the products are maintained under substantially the same pressure and temperature existing in the heating coil for a period of time sufficient to bring about conversion of a substantial portion of the gases to liquid hydrocarbons. The gases may be submitted to conversion conditions for a period of time ranging from 10 to 100 seconds. The reaction coil is preferably of larger cross-sectional area than the heating coil and may in some cases take the form of a chamber. The reaction coil is preferably enclosed in a suitable housing 21 which will permit controlled passage therethrough of a heating or cooling medium such as combustion gas or air in order to control the temperature in the reaction coil. It is necessary to provide for both heating and cooling of the reaction coil since the net heat of reaction of the hydrocarbons may be either endothermic or exothermic, depending upon the unsaturate content of the gases charged to the system. The reaction products upon leav-

ing the reaction coil through line 22 are immediately and quickly chilled in exchanger 11 to a temperature below that at which conversion takes place, by indirect heat exchange relation with gases charged to the system. The temperature is preferably lowered to below the temperature at which polymerization occurs, for example 700° F. or lower, but in no case should the temperature be below that at which satisfactory fractionation of the products may be obtained. The chilled products may be further cooled as conditions require by passage through heat exchanger 23, the products then passing through line 25 controlled by valve 27 into the lower portion of primary fractionator 29. At valve 27 the pressure may be reduced if necessary so that the pressure in the primary fractionator will be maintained between approximately 325 to 450 pounds per square inch. The pressure and temperature of the products entering fractionator 29 are so regulated that C₄ and lighter material can be separated as an overhead product and so that the overhead products can be handled without compression. Vaporization and fractionation of the products takes place in tower 29. Nothing heavier than C₄ hydrocarbons is taken off overhead. The bottoms will contain all material boiling above C₄ hydrocarbons as well as some C₄ and lighter hydrocarbons. A portion of the bottoms from fractionator 29 may be returned to the fractionator as reflux by means of line 31, valve 32, pump 34, cooler 36, and line 38, the principal portion being passed through line 31 into approximately the mid-section of secondary fractionator 39. This fractionator may be maintained at a pressure of 175 to 275 pounds per square inch and functions principally as a debutanizer, the overhead comprising predominantly C₃ and C₄ hydrocarbons. Additional heat for proper fractionation may be supplied from outside sources by means of reboiler 40. The liquid, now substantially free from C₄ hydrocarbons and lighter gases, is withdrawn from the bottom of reboiler 40 through line 41 and heater 42 and passed through line 43 to distillate fractionator 44. The debutanized liquid is heated in heater 42 to a sufficient temperature to remove substantially all motor fuel boiling range hydrocarbons overhead from distillate fractionator 44. Open steam may be fed into fractionator 44 through line 45 and valve 46 to facilitate the distillation. Distillate fractionator 44 may be operated at a pressure of 20 to 100 pounds per square inch. Additional heat for proper fractionation may be supplied by means of reboiler 47. The bottoms stripped of gasoline boiling fractions are removed from reboiler 47 through line 48 and withdrawn from the system. Motor fuel boiling range hydrocarbon vapors are taken from distillate fractionator 44 through line 49, completely condensed to liquid in cooler 51, and collected as a liquid product in accumulator 53. End point distillate motor fuel is removed from the system through line 55. A portion of the end point distillate may be returned to distillate fractionator 44 as reflux by means of pump 57, valve 59 and line 61.

Returning to secondary fractionator 39, the vapor overhead comprising principally C₃ and C₄ hydrocarbons is removed through line 63, condensed in cooler 65 and collected in accumulator 67. Any uncondensed material may be vented from the system through line 69 and valve 71. The liquefied condensate comprising principally C₃ and C₄ hydrocarbons may be withdrawn from

accumulator 67 by means of line 72, pump 73, valve 74, line 75, and line 71 and returned as a recycle stock to fresh feed line 1 wherein it is mixed with the fresh feed charged to the system. A portion of the condensate withdrawn from accumulator 67 may be returned to secondary fractionator 39 as reflux by means of line 78 and valve 79.

The overhead vapors from primary fractionator 29 comprising C₄ and lower hydrocarbons together with hydrogen is withdrawn from the fractionator through line 83, partially condensed in cooler 81 and collected in separator 83 wherein the liquid and vapors are separated under such conditions of temperature and pressure that the major portion of C₃ and C₄ hydrocarbons is condensed. The liquid condensate is withdrawn from separator 83 by means of pump 85, line 87, valve 89, and cooler 91, withdrawn from the cooler through line 92, passed into line 75 wherein it is mixed with condensate withdrawn from accumulator 67, and returned through line 77 to fresh feed line 1 and therein further mixed with fresh gas charged to the system. A portion of the liquid condensate recovered in separator 83 may be returned as reflux to primary fractionator 29 by means of line 93 and valve 95. Uncondensed gases are withdrawn from separator 83 through line 97, valve 99, and line 101, cooled in cooler 103 and fed to the lower portion of high pressure absorber 105 wherein the gases may be contacted with, and a portion thereof absorbed in, gas oil or other suitable liquid absorptive medium. The pressure at which the high pressure absorber operates may be approximately 300 to 500 pounds and the temperature about 60° to 120° F. The pressure and temperature conditions maintained in this absorber as well as the ratio of gas oil circulated depend somewhat upon the composition of the gases fed to the absorber, the object being to absorb C₂ hydrocarbons and heavier fractions and leave unabsorbed, methane and hydrogen. The unabsorbed gases including the methane and hydrogen and some C₂ hydrocarbons may be withdrawn from the top of the absorber through line 107 and removed from the system. Rich oil bottoms are withdrawn from the bottom of the absorber through line 109 and pump 111, passed through heat exchanger and heater 113 and 115 respectively, wherein the temperature of the rich oil is raised to desired flash tower conditions, and then through line 117 into flash tower 118 wherein the rich oil is stripped of dissolved low boiling hydrocarbons, principally C₂ fractions. Flash tower 118 may be operated at a pressure of approximately 350 to 450 pounds, a bottom temperature of 300° to 400° F. and a top temperature of 100° to 200° F., the conditions maintained being such as to substantially completely strip the rich oil of any C₂ hydrocarbons. The pressure maintained in flash tower 118 is always sufficiently high so that C₂ fractions in the overhead vapors may be charged back to the feed tank through line 119 without compression and will there, to a large extent, liquefy when mixed with the heavier portion of the charge. The partially stripped absorption medium is removed from the flash tower through line 121 and passed to the mid-section of absorber oil stripper 123 maintained at lower pressure than flash tower 118, and any remaining normally gaseous hydrocarbons such as C₃ and C₄ fractions removed overhead. Additional heat to facilitate the fractionation may be supplied by reboiler 125. Low

boiling hydrocarbon fractions vaporized in the stripper may be removed from the top of the stripper through line 127, condensed in cooler 129 and collected in accumulator 131. The pressure at which the absorber oil stripper is operated, while less than that at which flash tower 118 is operated, is sufficiently high to condense C₃ and C₄ hydrocarbons in cooler 129. Any uncondensed hydrocarbons may be removed from the top of accumulator 131 by means of valve 133 and line 135. Condensate recovered in accumulator 131 is removed through line 137, pump 139, valve 141, line 142 and valve 143 and passed into line 75 wherein it is mixed with condensate recovered from the primary fractionator 29 and secondary fractionator 39 and returned to fresh feed line 1 wherein a further mixture with fresh gases charged to the system occurs. A portion of the condensate withdrawn from accumulator 131 may be supplied as reflux to the top of flash tower 118 by closing or partially closing valve 143 in line 142 and passing it through line 144 controlled by valve 144 and line 150. A portion of the condensate withdrawn from accumulator 131 may also be returned to stripper 123 as reflux through line 145 and valve 146. Alternatively, reflux may be supplied to the flash tower by withdrawing liquid feed from tank 5 by means of line 7, pump 9, line 151, control valve 152, and line 150.

Lean absorption oil from which the low molecular weight hydrocarbons have been completely stripped in stripper 123 is removed from reboiler 125 through line 153 by means of pump 154, passed through line 155, exchanger 113, wherein the temperature is reduced by indirect heat exchange with bottoms from the absorber, passed through line 156, further cooled in cooler 157 and returned through line 159 to the top of high pressure absorber 105.

While I have set forth one means by which my process may be practiced, it is apparent that there may be many modifications within the scope of my invention. One alternative means of operating is shown on the drawing wherein fresh feed gas charged to the system is charged through line 1, valve 161, line 163 to line 63 wherein it is mixed with overhead vapors from secondary fractionator 39 and passed to cooler 65 and accumulator 67. When the fresh feed gases are charged to the system by the means just described, valve 2 is closed. In this method of operation condensate removed from accumulator 67 containing the fresh material charged to the system, is removed through line 72, pump 73 and line 165, valve 167 being opened and valve 74 closed. The mixture then passes through line 93 into the top of primary fractionator 29. Valve 95 may be open or closed or in an intermediate position, depending upon the amount of reflux required. Usually, however, valve 95 will be closed in this method of operation. It is apparent that the fresh feed may be split and a portion of the feed charged to the system by each of the means described.

It will be seen, therefore, that C₂ fractions as well as C₃ and C₄ fractions are separated from the reaction gases and returned to the feed tank for recycling through the conversion zone together with fresh feed gases charged to the system, all without the use of any gas compression steps.

The advantages of my process will be more clearly apparent from the specific examples of

several commercial scale operations, the critical data of which are set forth below:

In all of the foregoing examples, the fresh gases charged to the system are composed substantially entirely of C₃ and C₄ hydrocarbon fractions. In calculating the yields, the net fresh feed is the C₃ and heavier fractions entering the unit less the C₃ and heavier fractions, if any, leaving the unit in the residue gas. In this way the polymerization process is not charged for purposes of calculation with C₃ and heavier fractions which may escape as residue gas through

incomplete or improper separation from lighter gases which are withdrawn from the system. In all of the runs indicated, the same heating and reaction coils were used. Reaction time is computed as the period in seconds during which the charge is subjected to the average temperature of the reaction coil which, for the examples cited, lies within the range of 1060° F. to 1085° F. The reaction time was substantially the same for all

10 of the runs in Tables I and II.

A comparison of Runs 1 and 2, Table I, indicates the effect on yield of increasing the proportion of C₂ and C₃ fractions recycled to the conversion zone with the fresh feed. Although the 15 conditions of temperature, pressure, recycle ratio and composition of fresh feed are substantially the same in both cases, the yield of motor fuel end point polymer gasoline is increased by 1.2 gallons per 1000 cubic feet of net fresh gas charged in Run 2. This is due to the increased amount of C₂ and C₃ fractions in the recycle charged to the conversion zone. There is some difference in amount of C₃ and C₄ fractions in the composition of the net fresh feed, Run 1 having 38.7 mol % of C₄ while Run 2 shows but 27.6 mol % C₄ fraction. If this difference in C₄ content were the only difference between Runs 1 and 2, it would be expected that the yield of polymer gasoline from Run 1 would be the highest since 20 it is well known in the art that under the operating conditions indicated, the yield of polymer gasoline is higher from C₄ fractions than from C₃ fractions, the proportion of unsaturates being substantially the same in each case. It is thus 25 apparent that in contrast to what might well be expected, increasing the proportion of C₂ and C₃ fractions returned to the conversion zone, increases the yield of polymer gasoline.

In Table II, results of Runs 3, 4 and 5 are shown 30 wherein under like operating conditions the effect of increasing still further the proportion of C₂ fraction recycled to the conversion zone is clearly brought out. This increase of C₂ fractions is accomplished by obtaining additional C₂ fractions from the residue gas thereby increasing the proportion of C₂ in the recycle and by increasing the recycle ratio which brings about a further increase in the proportion of C₂ fraction charged to the conversion zone with the fresh feed. As 35 the amount of C₂ recycled is increased, the yield of polymer gasoline is increased. Run 3 having 10.3 mol % of C₂ fraction in the feed to the heating coil produced 39% by weight of polymer gasoline. When the C₂ fraction in the heating coil feed was increased to 17.4 mol % as in Run 5, the yield in weight % of polymer gasoline increased to 54.5, a figure entirely unexpected in 40 view of the teaching of the art since C₂ fractions do not polymerize to gasoline boiling range hydrocarbons to an appreciable degree under the operating conditions shown herein. The yield is even more unusual when the composition of the net fresh gas charged to the system is considered, Run 5 having 24 mol % C₄s and Run 3 only 29 mol % C₄s.

The increased yield is not due entirely to the 45 increased C₂ recycle but is also due to high recovery and recirculation of C₃ fractions and to adjustment of conversion conditions whereby high recycle ratios may be obtained.

50 Although specific methods of converting substantially saturated low molecular weight hydrocarbons have been shown and described, it is to be understood that the invention is not limited 55 to the specific form shown and described but is 60 to the specific form shown and described but is 65 to the specific form shown and described but is 70 to the specific form shown and described but is 75 to the specific form shown and described but is

to be interpreted broadly and limited only by the following claims.

I claim:

1. Process for converting predominately saturated hydrocarbons consisting of substantially C₃ and C₄ hydrocarbons to hydrocarbons boiling within a range suitable for liquid motor fuel comprising subjecting said gases in a reaction zone to pressures of 400 to 2500 pounds per square inch and temperatures of 1000° to 1250° F., maintaining such gases in a heated and compressed state for a sufficient period of time to convert a substantial portion of said gases to liquid motor fuel hydrocarbons, said conditions of pressure, temperature and time being such that C₂ hydrocarbons do not polymerize to any appreciable degree, fractionating the converted products into liquids consisting chiefly of hydrocarbons above C₄, a fraction containing the major portion of the C₄, C₃ and C₂ hydrocarbons, the C₂ hydro-

20

carbons including a major portion but not all of the ethane and ethylene, and a fraction containing the major portion of the hydrogen and methane, eliminating the last mentioned fraction from the system, recycling and mixing the second mentioned fraction with the said predominately saturated hydrocarbons consisting of substantially C₃ and C₄ hydrocarbons at such a rate as to maintain a recycle ratio of approximately 2.9 to 10 to 6, the unsaturated content of the resulting mixture charged to the reaction zone being below that which will cause rise in temperature during reaction.

2. Process in accordance with claim 1 in which 15 sufficient gas containing ethane and ethylene is recycled so that the mixed gas charged to the reaction zone contains approximately 17.4 mol per cent of C₂ hydrocarbons.

JOHN W. THROCKMORTON.
